UNITED STATES PATENT OFFICE

105,043

DESIGN FOR A COMBINED MIRROR AND HAT RACK MOUNTING

John C. Van Aken, Ridgway, Pa.

Application May 8, 1937, Serial No. 69,247

Term of patent 7 years

To all whom it may concern:

Be it known that I, John C. Van Aken, a citizen of the United States, residing in Ridgway, in the county of Elk and State of Pennsylvania, have invented a new, original, and ornamental Design for a Combined Mirror and Hat Rack Mounting, of which the following is a specification, reference being had to the accompanying drawing, forming a part thereof.

Figure 1 is a front perspective view of a combined mirror and hat rack mounting, showing my new design.

Figure 2 is a side elevational view of the same, and

Figure 3 is a top plan view of the same.

The characteristic features of my design reside in the portions shown in solid lines.

I claim:

The ornamental design for a combined mirror and hat rack mounting, as shown and described.

JOHN C. VAN AKEN.
